NICHOLAS S. VEDDER, OF TROY, AND TOBIAS S. HEISTER, OF LANSINGBURG, NEW YORK, ASSIGNOR TO NICHOLAS S. VEDDER.

Design No. 3,863, dated February 22, 1870.

DESIGN FOR A STOVE-PLATE.

The Schedule referred to in these Letters Patent and making part of the same

---

To all whom it may concern:

Be it known that we, NICHOLAS S. VEDDER, of Troy, and TOBIAS S. HEISTER, of Lansingburg, in the county of Rensselaer, and State of New York, have jointly invented and produced a new and original Design for Plates of a Cooking-Stove, of which the following is a specification, reference being had to the accompanying photographic illustration.

The distinguishing feature of this design is the compound central ornament, *a*, on a plane surface, *b*, surrounded by the ornamental border-molding *c*, all shaped and arranged upon a door or doors, or plate or

plates of a cooking-stove, so as to appear as represented in the aforesaid photograph.

What we claim as our invention or production, and desire to secure by Letters Patent, is—

The design for a door or doors, or a plate or plates of a stove, as herein specified and shown.

NICHOLAS S. VEDDER.
TOBIAS S. HEISTER.
